CLAIM

The ornamental design for a teakettle, as shown and described.

DESCRIPTION

FIG. 1 is a top plan view of a teakettle showing my new design;

FIG. 2 is a right side elevational view thereof, the left side elevational view being substantially similar thereto, the teakettle cover knob having a truncated, ovoidal upper part and a cylindrical lower part;

FIG. 3 is a front elevational view thereof;

FIG. 4 is a rear elevational view thereof;

FIG. 5 is a bottom plan view thereof;

FIGS. 6 and 7 are vertical sectional views as taken along the lines 6—6 and 7—7, respectively, in FIG. 1, the teakettle cover knob being shown in full lines in both views and the teakettle handle in full lines in FIG. 6.

FIG. 3

FIG. 4

FIG. 5
